United States Patent Office.

WILLIAM G. KENYON, OF WAKEFIELD, RHODE ISLAND.

Letters Patent No. 95,807, dated October 12, 1869.

IMPROVEMENT IN MOWING-MACHINES.

The Schedule referred to in these Letters Patent and making part of the same.

To all whom it may concern:

Be it known that I, WILLIAM G. KENYON, of Wakefield, in the county of Kent, and State of Rhode Island, have invented certain new and useful Improvements in Mowing-Machines; and do hereby declare the following to be a full and correct description thereof, reference being had to the accompanying drawings, making part of this specification, and to the letters and numbers of reference marked thereon, similar letters and numbers being used in all the figures to denote the same part.

In these drawings—

Figure 1 is a vertical section of the machine, taken through from front to back near the middle.

Figure 2 is a top view, the seat being removed.

Figure 3 is a top view of the parts for moving the knife-bar, the cover being removed.

Figure 4 shows a guard-finger with top removed.

Figure 5 is a side view of guard-finger.

Figure 6 is a cross-section of same, taken through in the direction of the line x in fig. 5.

The nature of my improvements consist—

First, in making an auxiliary frame, supported at one end by the axle, and at the other end by a wheel running on the ground, to take the weight of the cutting-apparatus when raised from the ground, instead of leaving it on the pole and horse.

Second, in the motion for the cutting-bar being more directly communicated, and a cover provided to keep the grass and dirt out of it, and construction of the guard-fingers.

The construction is as follows:

A is the main frame, placed on the axle C, between the two driving-wheels B and D.

G is an auxiliary frame, consisting of a bar, with one end on the axle, between the side of the main frame and the driving-wheel nearest the cutter, and the other supported in front by a wheel, S, and a brace-bar fastened to the other in front, and extending diagonally back to the axle near the other side of the main frame. This auxiliary frame projects out in front of the axle, and provides a steady support, not varying with the up-and-down motion of the pole, to hold the working-parts that raise and lower the cutter-frame, and determine the height at which it shall cut, with great uniformity.

A pulley, t, with a ratchet-wheel, v, is fastened to a short shaft, turning in a bearing in this frame G, and on the outer end of the shaft, a small gear-wheel, o, is secured.

A little back of this shaft is a segment of an inside gear-wheel, r, with a lever, j, attached to it, the segment being pivoted to the frame G, and its teeth meshing into the pinion o.

A chain, p, is attached to the front end of the

main frame, and passing up to the pulley t, is fastened to it.

Another chain, w, is attached to the front end of the shoe E, and carried up to the frame G, and hooked to it, for the purpose of regulating the drop of the cutter-bar J, when raised to clear obstructions.

The shoe E is fast to the guard-bar I, and is hung in standards e e, attached to the main frame A.

Motion is conveyed to the knife-bar x by a segment-gear, o', moving on a pivot in the finger-bar or shoe, and meshing into a rack made in the back of the cutter-bar; a connecting-bar, g, having one end pinned to the segment o', and the other end on the crank-pin in plate c.

This plate is fast to the shaft f, which receives its motion through the gear-wheels d and r and the pinions i i, which mesh into the inter al gear-wheels s' on the driving-wheels.

Y is a cover, which keeps the grass and dirt out of the segment and rack t: t move the cutter-bar, and is hinged at the forward end, to admit of its being opened for oiling, &c.

A draught-chain, H, is fastened to the pole j, and passing through a staple in the pole, is hooked into a plate, b, on the front end of the frame A, there being several holes in the plate, of different heights, to vary the direction, if desired.

The guard-finger is made with two recesses, to hold the ledger-blades, which consist of two plates, z z, one in each of the two recesses of each finger, (see fig. 4.) They may be made with pivots on their inner corners, fitting into sockets in the ends of the recesses; or they may be made to turn on the lower corners of their inner edges, so as to roll their outer edges up against the cutters, and make a close cut. Springs may be put under them, to assist in pressing them up, if necessary.

When the plates are not made with pivots, projections, n n, (see figs. 4 and 5,) are made on the edge of the guard-fingers, to keep them in place.

The outer edges of the blades are made with lips, h h, (see fig. 6,) which project down over the sides of the guard-fingers, to keep the grass and dirt from clogging them up.

I am aware that ledger-blades have been constructed in a variety of forms, and secured to the fingers in various ways, but not as above described.

The operation is as follows:

The driving-wheels B D give motion to the pinions i i by the gear-wheels s' s', which drive the shaft, and gear-wheel r gearing into the pinion d on the shaft f, to which the plate e is fastened. A connecting-rod, g, conveys motion from a pin in this plate to the segment-gear o', which moves the knife-bar x

back and forward, to cut the grass against the guard-fingers, as usual.

When it is necessary to raise the cutting-apparatus, to pass obstructions, by drawing back the lever *j*, the segment *e* will turn the pulley *t*, and raise the frame *A* and all attached to it, and it can be held up by pushing in the pawl-lever *m*.

By hooking up the chain *w*, to any desired height, the cutting-apparatus will always drop back to the proper place, when released, after having been raised to pass an obstruction.

The draught-chain *H* may be hooked higher or lower in the plate *b*, so as to vary the direction of the draught.

The weight of the pole *j*, and also of the driver, may be supported by the auxiliary frame *G*, if desired to relieve the horses.

Having thus described my improvements,

What I claim as my invention, and desire to secure by Letters Patent, is—

1. The segmental gear *o'*, in combination with the cutter-bar *x* and the connecting-bar *g*, as and for the purpose specified.
2. The chain *w*, in combination with the shoe *E* and auxiliary frame *G*, substantially as and for the purpose set forth.
3. The cover *Y*, in combination with the parts that move the knife-bar, substantially as specified, and for the purpose set forth.
4. The guard-finger, in combination with the ledger-blades, constructed substantially as described, and for the purpose specified.

WM. G. KENYON.
